Primary Examiner — T Chase Nelson*Assistant Examiner* — Kelly L Gross(74) *Attorney, Agent, or Firm* — Kenja IP Law PC(57) **CLAIM**

The ornamental design for an eye drop container, as shown and described.

DESCRIPTION

FIG. 1 is a front perspective view of an eye drop container showing our new design;

FIG. 2 is a front view thereof, the back view being an identical image thereof;

FIG. 3 is a top view thereof;

FIG. 4 is a bottom view thereof;

FIG. 5 is a right side view thereof, the left side view being an identical image thereof;

FIG. 6 is an enlarged sectional view taken along line 6-6 in FIG. 2 thereof; and,

FIG. 7 is a sectional view taken along line 7-7 in FIG. 3 thereof.

The broken lines illustrate portions of the eye drop container that form no part of the claimed design.

1 Claim, 7 Drawing Sheets
